SPRING UNIT FOR MATTRESSES, CUSHIONS,
AND THE LIKE

Gustave P. Johnson, Waukegan, Ill.

Application October 6, 1949, Serial No. 119,894

3 Claims. (Cl. 5—269)

1

The producers of spring structures, for use with various types of sitting and sleeping furniture, have always striven to achieve that degree of yielding resistance which ensures the maximum comfort to persons differing widely in weights commensurate, however, with acceptability in appearance, durability in service, and reasonable-ness in cost. Generally, springs of the spiral or hourglass type have been used for seats, cushions and mattresses for various kinds of such furni-ture. The problem in producing this type of spring has been to get such a balance in the weight-resisting flexibleness of the successively smaller convolutions or coils of the individual springs as would avoid concentration of the weight too quickly and locally on the interme-diate, more resistant, and smaller coils with their reduced area of contact with the upholst-ery. Also, there has been the problem of appropriately tying together the several springs of a spring unit so as to secure the desired lateral distribution of varying pressures to which the spring structure is normally subjected.

The main objects of this invention, therefore, are to provide an improved spring unit for seats, cushions, and mattresses and the like; to pro-vide in a spring unit an improved form of com-ponent springs wherein the several convolutions or coils receive more nearly uniform flexing when the spring structure is subjected to weights or pressures than has been possible with spring units heretofore produced; to provide for the spring unit an improved form and arrangement of the top and bottom interconnecting helicals which will permit the seat cushion or mattress to afford a comfortable support for persons of materially differing weights; and to provide an improved spring unit cooperatively embodying the afore-said features so as to make available a seat, cush-ion or mattress possessing greater comfort and durability than has been obtainable with similar structures heretofore available.

In the accompanying drawings:

Figure 1 is a side elevation, partly sectional, of a mattress embodying a spring unit constructed in accordance with this invention, the cross-sec-tional portion indicating the compression that takes place when a concentrated load is applied at a localized point;

Fig. 2 is an enlarged, plan view of a section of a spring unit embodying this invention;

Fig. 3 is a further enlarged side elevational view of an individual spring comprised in this invention, the spring being shown in its fully extended position which is free of a load; and

2

Fig. 4 is a similar view showing the relative de-gree of flexing of the several coils of the spring when the spring is subjected to axial pressure.

In a spring unit embodying this invention a plurality of load-sustaining wire springs 5 are arranged in parallel rows within the area of the desired seat, cushion, or mattress, and tied together by wire spring helicals 6.

The springs 5 are of the spiral or hourglass type 10 wherein the successive coils or convolutions from the ends of the spring inwardly are of decreasing diameter—assuming that the term “diameter” may be appropriately used in defining the spiral character of these coils or convolutions. The de-crease in the diameter of the successive coils is between one-fourth and one-fifth, preferably close to the latter. In the case of a five-coil spring, this will result in the diameter of the in-nermost or middle coil 7 being reduced by less than half the diameter of the end or outermost coils 8 of the spring, the diameter of the inter-mEDIATE coils 9 being graduated proportionately.

As shown in Fig. 4, when a spring coil of this description is subjected to axial pressure, the middle coil 7 and the intermediate coils 9 yield at very nearly the same rate as the end coils 8, es-pecially during the earlier stages of spring com-pression; approximately this same rate of yield-ing continues through a further compression of 30 the spring 5 until its height is reduced by sub-stantially one-half.

The spring-tying helicals 6 and 6a employed in this improved spring unit, which may be of a con-ventional nature, extend along both sides of the 35 structure between the load-sustaining springs 5. The helicals 6 are wound around the end coils of the springs 5 so as to tie adjacent springs togeth-er, as shown at 10 in Fig. 2. However, in this struc-ture, as shown in Fig. 3, the helicals 6a along 40 the top side of the structure are heavier gauged and possessed of yielding capacities different from those of the lighter gauged helicals 6 extending along the bottom side of the structure. This dif-ference in yielding may be attained by using heli-cals of differing pitch, or by wire of different tempers or different gage. In the embodiment herein shown the helicals are formed of wire of differ-ing gages, as clearly appears from Figs. 3 and 4. This makes possible accommodating such 45 a spring structure to persons of different weights, or to a different number of persons, or to other circumstances. This accommodation would be effected by so positioning the spring unit that the helicals of the greater or less yielding capacity are 50 disposed at the top or at the bottom of the struc-

ture, as the circumstances seem to require. A spring structure of this improved form and arrangement would be covered with a suitable fabric casing 11 whereon other covering or upholstery can be applied.

The special features of construction inherent in the present spring unit make possible a reduction in the length of the springs without in any degree impairing the cushioning effect thereof. This reduction may amount to 1" or so in a spring structure of conventional size and capacity. As above noted, the cushioning effect is largely concentrated at the coils toward the end of the springs. Yielding of the springs in response to a load is affected by the interconnecting helicals which serve to distribute a localized load over a considerably wider area. Where the helicals are stiffer, the distribution of the load is confined to a smaller area, whereas with interconnecting helicals having a greater resiliency the load is distributed over a wider area. As the result, it is possible to utilize on one side of the spring unit a set of interconnecting helicals which are relatively stiff, and on the opposite side thereof of another set of interconnecting helicals which are relatively flexible; a load imposed on the spring unit side having the stiffer helicals will be distributed less widely than will the same load if imposed upon the opposite side of the spring unit where the more yieldable helicals are located. This circumstance is relied upon to adapt the spring unit for the support of persons varying widely in weight. For example, for a person weighing close to 200 lbs. the spring unit should be disposed with the stiffer helicals uppermost, and the opposite disposition should be made for a person whose weight is considerably less, say 100 lbs. Not only will the spring unit be better adapted to sustain the weight when so disposed in relation to the load which is to be supported, but much greater comfort will be afforded to the person who is using the mattress, cushion, or seat.

Modifications and variations of the construction herein shown and described may be resorted to without departing from the spirit or coverage of the appended claims.

I claim:

1. A spring structure of the class described, comprising a plurality of rows of coiled springs, a plurality of spring helicals of uniform yielding capacity at the top of the spring structure, a plurality of spring helicals of uniform yielding capacity at the bottom of the spring structure, said spring helicals extending along said rows of springs at the inner and outer sides thereof and

5 connected to the end coils of each spring, the spring helicals at the top and bottom of the spring structure being of different yielding capacities, whereby the opposite sides of said structure yield differently to equal pressures.

2. A spring structure of the class described, comprising a plurality of rows of coiled springs, a plurality of spring helicals of uniform yielding capacity at the top of the spring structure, a 10 plurality of spring helicals of uniform yielding capacity at the bottom of the spring structure, said spring helicals extending along said rows of springs at the inner and outer sides thereof and connected to the end coils of each spring, the 15 spring helicals at the top of the spring structure being of heavier gauge material than the spring helicals at the bottom of the spring structure, whereby the top of the spring structure will be less yielding than the bottom of the same and 20 be better adapted to support the weight of a heavy person.

3. A spring structure of the class described comprising a plurality of rows of coiled springs, a plurality of spring helicals of uniform yielding 25 capacity at the top of the spring structure, a plurality of spring helicals of uniform yielding capacity at the bottom of the spring structure, said spring helicals extending along said rows of springs at the inner and outer sides thereof and 30 connected to the end coils of each spring, the spring helicals at the top of the spring structure being of lighter gauge material than the spring helicals at the bottom of the spring structure, whereby the top of the spring structure will be 35 more yielding than the bottom thereof and better adapted to support comfortably a person of light weight.
